UNITED STATES PATENT OFFICE.

NEWMAN A. RANSOM, OF CHICAGO, ILLINOIS, ASSIGNOR OF ONE-HALF TO
JOHN F. GREENLEAF, OF SAME PLACE.

GAS-BURNER AND CARBURETOR.

SPECIFICATION forming part of Letters Patent No. 333,671, dated January 5, 1886.

Application filed July 21, 1885. Serial No. 172,230. (No model.)

To all whom it may concern:

Be it known that I, NEWMAN A. RANSOM, of Chicago, in the county of Cook and State of Illinois, have invented certain new and useful Improvements in Gas-Burners and Carburetors; and I do hereby declare the following to be a full, clear, and exact description of the same, reference being had to the accompanying drawings, forming a part of this specification, and to the figures and letters of reference marked thereon.

The object of my present invention is to increase the illuminating power of gas as ordinarily supplied to dwellings, &c., by admixture therewith of a proper proportion of hydrocarbon vapor; and to this end my said invention consists in the combination, arrangement, and construction of a carbureting attachment for application to gas-burners supplied with illuminating-gas.

In carrying out my said invention I apply to the end of the supply-pipe and above the burner a carbureting apparatus having the following characteristics, viz: a reservoir or chamber charged with hydrocarbon and provided with an aperture or opening for the passage of the heated products of combustion, whereby the hydrocarbon-supply is maintained at an elevated temperature; an induction passage or passages connecting the gas-supply pipe with the interior of the said reservoir or chamber; and an eduction passage or passages leading from said reservoir or chamber to the burners, whereby the gas as it comes from the supply-pipe is conducted through the reservoir or chamber and in contact with the hydrocarbon contained therein and delivered to the burners, and the heated products of combustion or a portion thereof being directed and conducted through or in proximity to the chamber or reservoir impart sufficient heat to the hydrocarbon to gradually vaporize the latter and cause it to mingle with the gas.

The invention further consists in the combination, with an apparatus having the characteristics above described, of a shade or reflector applied beneath the chamber or reservoir, and serving not only to reflect the light,

but also to assist in directing the products of combustion into the aperture or passage in the carburetor.

It also consists in passing the tube or pipe leading from the chamber or reservoir to the burners through the passage for the heated products of combustion, whereby the gas after it leaves the carburetor is maintained at a high degree of temperature and its illuminating power augmented; and it further consists in certain minor combinations and arrangements of parts, all as hereinafter more fully described, and pointed out in the claims.

In the accompanying drawings, Figure 1 represents in longitudinal section an improved apparatus for carrying out my said invention. Fig. 2 is a top plan view of the device shown in Fig. 1. Fig. 3 illustrates a modified form of the apparatus in vertical section.

Similar letters of reference in the several figures indicate the same parts.

The improved form of carburetor herein shown as illustrating the main features of my present invention and a practical mode of applying the same is composed of a metal casting, A, surrounding a central tube, B, to which it is connected at the lower end, forming a chamber or receptacle, C, for the reception of the hydrocarbon. The top of this chamber C is closed by a metal head or casting, D, provided with flanges d, or their equivalents, to receive and hold the upper edges of the casting A and tube B. This head or casting D is provided with a cross-piece or bridge, d', formed with two sets of openings or passages, d² and d³, the former, d², extending from the central passage or boss, d⁴, (to which the supply-pipe E is attached,) to the interior of the chamber C, constituting the induction-passages, and the latter, d³, extending from the interior of chamber C to the central passage or boss, d⁵, (to which the delivery-pipe E is applied,) constituting the eduction-passages. Attached to or cast integral with the head D is a downwardly-projecting collar or flange, d⁶, located between the induction and eduction passages, and serving to deflect or conduct the gas down toward the hydrocarbon contained within the chamber C, whereby the gas

as it passes from the supply-pipe through the chamber C and into the delivery-pipe E will be brought into contact and thoroughly mixed with the hydrocarbon vapor generated in the 5 chamber C. The delivery-pipe E extends through and projects some distance below the tube B, its upper end being attached to the boss d^o as by a screw-threaded connection, while its lower end is provided with a hollow 10 cap, e, to which a series of radial burners, e', are secured. Beneath the chamber C, and preferably to an extension of the tube B, is attached a reflector or shade, F, which, in addition to its usual functions, serves to direct the heated products of combustion arising 15 from the burners e' into the central passage or tube, B. A filling-orifice, f, is formed in the casing A on the head D, and closed with a suitable stopper, f', to prevent the escape 20 of gas.

The apparatus, as described, is adapted for use with various hydrocarbons; but is especially designed to receive what is known as "dry white" or "albo" carbon, which is introduced 25 into the chamber C in lumps or pieces and caused to generate or give off hydrocarbon vapor when heated.

It is found in practice that the carbureting-chamber C if made of cast-iron, as is usual, 30 is rather slow in getting heated to the desired degree, and that until so heated the maximum of brilliancy is not obtained, and this is more especially the case when fluid hydrocarbon—such as kerosene—is employed in the carburetor. In order to overcome this objection, and by facilitating the heating of the hydrocarbon 35 when the gas is lighted, thereby producing a brilliant light in a shorter time, I make provision for heating the gas before it enters the carburetor. Such an apparatus is illustrated 40 in Fig. 4, wherein H represents the gas-heater interposed in the supply-pipe and located, say, about three inches above the carburetor, and in position to be acted upon by the hot air 45 and products of combustion after passing through the carburetor. This heater H is preferably cast in a single piece of brass, or other suitable material, (it may be made of two or more sections, if desired,) with a plate or 50 diaphragm, h, resting upon studs or projections h', and operating to spread the gas, thereby exposing the latter to a larger heated surface.

The carburetor may, if desired, be inclosed 55 within an ornamental casing, I, of metal or other suitable material, and it may project or extend above the top of the chamber C, as shown in Fig. 4, serving not only to conceal the carburetor, but also to deflect the heated 60 air, &c., passing through the carburetor against the gas-heater H.

The amount of light given off from the burners and the degree of heat to which the carburetor is subjected can be regulated and controlled 65 by suitable cocks or valves—such, for example, as shown at J, Fig. 1—and, if de-

sired, the delivery-pipe can be made extensible by providing it with a sliding joint or section, as indicated in dotted lines in Fig. 4, whereby the position of the burners with respect to the carburetor can be varied. 70

The numerous advantages secured by the arrangement, combination, and structure shown and described will be apparent to any one skilled in the art. 75

By the location and arrangement of the carburetor above the burners ample provision is made for heating the carburetor and maintaining it in position where it cannot interfere with the proper diffusion and reflection of the light beneath the fixture. Not only is the hydrocarbon in the carburetor heated and maintained at the requisite temperature by the heat arising from the burners, but the gas is also heated both before and after it leaves the carburetor, thereby facilitating the operation of the carburetor at the start, and by partially or wholly fixing the mixed gases increasing the illuminating property and preventing condensation in the delivery-pipe. 85 90

I am aware that prior to my invention carbureting gas-burners have been constructed, in which the receptacle containing the hydrocarbon is placed over the illuminating-flame, and is adapted to be heated thereby, as shown, 95 for instance, in Patent No. 62,855, granted to J. Kidd, March 12, 1867, and I am also aware that devices for heating the gas before it reaches the carburetor have been employed, and therefore I do not desire to be understood as claiming these features, broadly. 100

I claim as my invention—

1. In a gas-burner and carburetor such as described, the combination of the hollow chamber or receptacle for the hydrocarbon provided with the central opening or flue, the cap or head for said chamber provided with induction-passages and eduction-passages, the supply and delivery pipes connected to the cross-piece or bridge of said cap, the said delivery-pipe extending through the opening and below the said chamber, and the burner applied to the lower end of the delivery-pipe, substantially as described. 105 110

2. In combination with the casing A and central tube, B, a head, D, provided with induction and eduction passages and a downwardly-projecting collar or flange, as described, the delivery-pipe connected to the head D, communicating with the eduction-passages and extending through the tube B, and the burner applied to the said delivery-pipe and located in line with but below the said tube B, substantially as described. 115 120

3. In a gas-burner and carburetor, such as described, the combination of the supply-pipe, the hollow casting and its diaphragm or spreading plate, the carburetor connected to the supply-pipe below the said hollow casting and provided with an opening for the passage of the heated products of combustion, and a delivery-pipe communicating with said carburetor. 125 130

retor and carrying burners located beneath the said opening in the carburetor, substantially as and for the purpose specified.

4. In combination with the hollow chamber, 5 the supply and the delivery pipes, the annular head or casting applied thereto and provided with the cross-piece or bridge formed with the induction and eduction passages communicating, respectively, with the supply and 10 delivery pipes, as set forth.

5. In a gas-burner and carburetor, such as described, the combination, with the receptacle or chamber and its heating flue or passage, of the burner located beneath said chamber and 15 adjustable with respect thereto, substantially as described.

6. In combination with the chamber and its central heating-passage, the head or casting applied to said chamber and provided with 20 induction and eduction passages, the delivery-pipe attached to said head and extending down through the central passage, and the burner located below the said chamber and 25 adjustably connected to the delivery-pipe, substantially as and for the purpose set forth.

7. In a carburetor for application to gas-burners, the combination, with the casing A and tube B, of the annular casting D, applied to the upper ends of the said casing and tube, 30 and provided with the cross-piece or bridge having the induction and eduction passages,

and the upper and lower bosses for attachment to the supply and delivery pipes, substantially as described.

8. The herein-described improved carbureting-burner, consisting, essentially, of the annular carbureting-chamber provided with the bridged cap-plate at its upper end and the deflecting plate at the lower end, the supply-pipe communicating with the induction-passages in the cap, a delivery-pipe communicating with the induction-passages in said cap and projecting through the central opening in the carbureting-chamber, and the burners applied to the delivery-pipe below the carbureting-chamber, substantially as described. 35 40 45

9. The combination, with the carbureting-chamber having the central heating-flue and supply and delivery pipes communicating with the interior of the chamber, said delivery-pipe extending through the heating flue and carrying the burners below, of the downwardly-projecting flange or collar located within the carburetor and intermediate the inlet and outlet passages for spreading the gas and conducting it toward and upon the hydrocarbon, 50 55 substantially as described.
